UNITED STATES PATENT OFFICE.

WARREN F. DREW, OF BOSTON, MASSACHUSETTS.

IMPROVEMENT IN HAIR-CRIMPERS.

Specification forming part of Letters Patent No. 177,926, dated May 30, 1876; application filed March 2, 1876.

To all whom it may concern:

Be it known that I, WARREN F. DREW, of Boston, Massachusetts, have invented an Improved Hair-Crimper, of which the following is a specification:

The object of my invention is to provide an implement for crimping the hair.

In the drawings, Figure 1 shows my crimper in use, and Fig. 2 the method of securing the braid *b* to the part *A*, by means of the piece of metal *c*, and Fig. 3 shows the body *A* of the crimper.

I make my improved hair-crimper as follows: The body *A* of the hair-crimper is made of wire, in the form shown in the drawing. A small piece of elastic braid, *b*, is then doubled over the extremity *a*. This is held securely in place by the piece of metal *c*, which is put on over the rubber braid, placed as described, and when put on, it is fastened by the two

parts *d* being forced down upon the braid. On the opposite side of the part *b* is the hook *e*. At the lower end of the braid is a ring, *f*.

When the crimper is in use, the hair, after being wound around the part *A*, as shown in the drawing, is kept in place by means of the braid *b*, brought around over the hair, and secured by the ring *f*, placed in the hook *e*.

What I claim, and desire to secure by Letters Patent, is—

The improved hair-crimper, consisting of the part *A* and elastic braid *b*, fastened together by means of the piece of metal *c*, the braid *b* having the ring *f* at its free end, whereby it may be secured to the hook *e*, substantially as above described.

WARREN F. DREW.
